United States Patent Office

Des. 195,899
Patented Aug. 6, 1963

195,899

BOTTLE OR SIMILAR ARTICLE

Victor Koenigsberg, Franklin Square, N.Y., assignor to Colgate-Palmolive Company, New York, N.Y., a corporation of Delaware

Filed Feb. 5, 1962, Ser. No. 68,636

Term of patent 14 years

(Cl. D58—8)

Fig. 1

Fig. 2

Fig. 3

Fig. 4

FIG. 1 is a side elevational view of a bottle, embodying
my new design;

FIG. 2 is an end elevational view thereof;

FIG. 3 is a top plan view thereof; and

FIG. 4 is a bottom plan view thereof.

I claim:

The ornamental design for a bottle or similar article,
as shown.
